UNITED STATES PATENT OFFICE.

JOHN SAMUEL CAMERON, OF MCKEESPORT, PENNSYLVANIA.

DESIGN FOR A COMBINED KNIFE AND FORK.

41,767.

Specification for Design.

Patented Sept. 12, 1911.

Application filed March 30, 1911. Serial No. 618,031. Term of patent 3½ years.

To all whom it may concern:

Be it known that I, JOHN SAMUEL CAMERON, a citizen of the United States, residing at McKeesport, in the county of Allegheny and State of Pennsylvania, have invented a certain new, original, and ornamental Design for a Combined Knife and Fork, of which the following is the specification, reference being had to the accompanying drawing, forming a part thereof.

The figure is a perspective view of the combined knife and fork, illustrating my new design.

I claim:—

The ornamental design for a combined knife and fork, as shown.

JOHN SAMUEL CAMERON.

Witnesses:

MAX H. SROLOVITZ,
CHRISTINA T. HOOD.
